UNITED STATES PATENT OFFICE.

CHARLES A. BOREIN, OF OAKLAND, CALIFORNIA.

WATER-HEATER.

1,052,792.

Specification of Letters Patent. Patented Feb. 11, 1913.

Application filed September 25, 1911. Serial No. 651,177.

To all whom it may concern:

Be it known that I, CHARLES A. BOREIN, a citizen of the United States, and residing at Eleventh and Broadway, in the city of 5 Oakland, county of Alameda, and State of California, have invented certain new and useful Improvements in Water-Heaters: and I do hereby declare the following to be a full, clear, and exact description of the 10 said invention, such as will enable others skilled in the art to which it most nearly appertains to make, use, and practice the same.

This invention relates to improvements in 15 water heaters, and consists in the novel construction and arrangement of the parts.

The objects accomplished are the production of a heater with a large heating area, whereby a small quantity of water is acted 20 upon by a relatively large quantity of heat, and capable also of serving as a boiler pedestal.

Broadly the invention consists of a conical water jacket having a corrugated inner 25 surface, adapted to be acted upon by the flame issuing from an annular Bunsen burner attached to the base of the cone. The apex of the cone is truncated and provided with a vent, to carry off the products 30 of combustion. The apex of the water jacket terminates in a threaded spud adapted to be screwed into the bottom of a "kitchen boiler" or reservoir. This spud is divided by a center wall, one passage 35 providing an outlet from the top of the water jacket, the other forming an internally cored passage leading to near the bottom of the water jacket and is adapted to conduct the cold water from the bottom 40 of the boiler to near the bottom of the water jacket: the other passage terminates in a threaded socket adapted to receive a pipe extending inside the boiler to near the top thereof, and adapted to conduct the hot 45 water from the top of the water jacket to near the top of the boiler, forming a thermosyphon internal circulation from the boiler through the heater and back into the boiler. A bridge across the apex of the cone inside 50 the heater, provides a socket for the reception of a pedestal, adapted to support the combined heater and boiler.

In the drawings: Figure 1 is a side elevation of a combined water heater and boiler, constructed in accordance with this invention. Fig. 2 is a vertical cross section of the heating member, taken on the line 2-2, (Fig. 4.) Fig. 3 is a fragmentary plan view from above of the same. Fig. 4 is a top view of the burner.

In detail the construction consists of the heating cone comprising the outer wall 1, the inner wall 2, closed at the bottom and terminating at the top in the spud 3. This spud is divided by the center wall 4, forming two passages 5 and 6. The mouth of the former is threaded to receive the pipe 8. The passage 6 continues downward to near the bottom of the water jacket, being formed by the wall 9 cast integral with the outer 70 wall, see Figs. 2 and 3. The cone of the water jacket is truncated which provides an escape vent 10, for the products of combustion. The bead 11 around the vent engages the flue 12 which is clamped there- 75 over, and adapted to receive a vent pipe.

The Bunsen burner comprises the annular chamber 13 provided with bolts by which it is bolted to the base of the heating cone, which is provided with the depending 80 flange 14. The aspirator neck 15 is bolted to and communicates with the annular chamber 13, and is adapted to be connected with the gas service, and is provided with the air inlets 16 for the proper admixture 85 of gas and air for combustion. The chamber 13 is provided with the outlet slots 17, adapted to play the flame against the heating surface of the cone.

To increase the heating surface the inner 90 wall 2 of the water jacket is augmented by corrugations. The overhanging convolutions being provided with depending spines 18, around and among which the flame from the burner plays in its passage through the 95 heating cone. To regulate the quantity of free air admitted to the heater, to support combustion, the circular damper pan 19 set on the pedestal 20 by the set collar 21 is provided. The air admitted to the cone, 100 except that passing through the burner, must pass between the inner circumference of the burner, and the outer circumference of the pan; the quantity being regulated by

raising and lowering the pan in an obvious manner. This pan also catches any condensation dripping from the heating surface, retaining it until evaporated by the heat. The opening 22 is provided in this pan for the introduction of a pilot light or taper for igniting the burner. For convenience in installing or removing the burner, it is divided as at 23 to pass the pedestal 20.

10 The heat absorbed by the inner wall 2 is communicated to the small body of water, confined between it and the outer wall 1.

If it is desired to use the heater independent of the boiler, the inlet opening 6 at the top is formed to receive a pipe connection with the water service: the outlet 7 being piped in the desired manner. In combination with a kitchen boiler as illustrated; for domestic purposes the boiler is installed in the usual manner, the inlet pipe 24 being connected to the water service and the outlet pipe 25 connected to the house service. The spud 3 is screwed into the central opening in the bottom of the boiler, the weight 25 of the whole being supported by the pedestal 20. The gas service is connected to the burner, and the sediment cock 26 screwed into the opening provided for it in the lowest point of the water jacket, this provides 30 a means for draining the system when accumulations make it necessary.

The apparatus operates as follows: When the burner is lighted the heat is absorbed by the heating cone and transmitted to the water. The products of combustion passing out through the vent pipe, which preferably leads outside the building. The water expanded by the heat rises from the heating cone and is forced up through the stand 40 pipe 8, and discharged near the top of the boiler, whence it passes through the outlet pipe 25 if a tap in the house service is opened. The hot water passing from the water jacket is replaced by water flowing 45 from the bottom of the boiler, through the passage 6 to the bottom of the water jacket. If no water is drawn from the system, an internal circulation is set up, the whole body of water circulating through the heater, 50 which progressively raises its temperature to the desired point. Should the heat from the gas flame be maintained the water within the boiler will expand and be forced out through the cold inlet pipe 24, until the 55 radiation is equal to the heat absorption; in this manner excessive pressure is provided against in the heating system.

It is preferable to cast the heating cone integral as illustrated; however modern practice in the metal arts makes it possible to build it up otherwise. Applicant therefore does not wish to be limited to the exact forms shown, and specifically described.

Having thus described this invention what

is claimed and desired to secure by Letters 65 Patent is:

1. In a water heater the combination with a reservoir, of a conical water jacket, having a corrugated inner surface, and terminating in a threaded spud screwed into the bottom 70 of the reservoir; a passage leading from the top of the water jacket to near the top of the reservoir, and a passage leading from the bottom of the reservoir to near the bottom of the water jacket; an annular burner 75 attached to the lower edge of the water jacket and adapted to discharge its flame against the corrugated inner wall of the water jacket; a vent opening through the apex of the conical water jacket; a flue 80 clamped over said vent opening; a bridge formed across the opening of the vent, adapted to receive a pedestal; a drip pan mounted on the pedestal, beneath the said burner; inlet and outlet service to said 85 reservoir.

2. A water heater comprising a conical water jacket, having a corrugated inner surface, and terminating in a threaded spud adapted to be screwed into the bottom of a 90 reservoir; a vent opening through the apex of the water jacket; an outlet passage from the top of the water jacket, through the said spud, terminating in a threaded socket; an inlet opening through said spud terminating 95 near the bottom of the water jacket; an annular burner secured to the base of the water jacket; a bridge across the said vent opening, adapted to receive a pedestal; a damper pan secured on the pedestal below 100 the burner.

3. A water heater comprising a conical water chamber having an internal heating chamber open at its bottom and provided with a vent opening at its apex, said water 105 chamber being provided with inlet and outlet openings at the apex thereof and separated by a partition wall, and a burner secured to the base of said heating chamber.

4. A water heater comprising a conical 110 water jacket having an augmented internal heating area, and terminating in a threaded spud; an outlet opening through the spud from the top of the water jacket, and an inlet opening through the spud internal and 115 formed integral with the wall and terminating near the bottom of the water jacket; and a burner secured to the base of the conical heating member.

5. A water heater comprising a conical 120 water jacket having a corrugated inner wall with depending spines; a vent opening through the apex of the water jacket, and a burner secured to the base of the water jacket; inlet and outlet openings from said 125 water jacket, forming a threaded spud extending above the water jacket on the axis of the cone.

6. A water heater comprising a conical heater member provided with a threaded spud at its apex, said spud being provided with inlet and outlet openings, vent openings being also provided in the apex of said heater member, and means for heating said conical member.

7. A hot water heater comprising a hollow heater member provided with a threaded spud having inlet and outlet openings,

vent openings being formed in said heater member adjacent said spud, and means for heating said member.

In testimony whereof, I have hereunto set my hand this 23d day of August 1911.

CHARLES A. BOREIN.
